UNITED STATES PATENT OFFICE.

ANDREW KLAY, OF BLUFFTON, OHIO, ASSIGNOR OF ONE-HALF TO CHRISTIAN WEISS, OF JENERA, OHIO.

RATCHET-DRILL.

SPECIFICATION forming part of Letters Patent No. 636,208, dated October 31, 1899.

Application filed June 26, 1899. Serial No. 721,890. (No model.)

To all whom it may concern:

Be it known that I, ANDREW KLAY, a citizen of the United States, residing at Bluffton, in the county of Allen and State of Ohio, have 5 invented a new and useful Ratchet-Drill, of which the following is a specification.

My invention relates to improvements in ratchet-drills especially adapted for use in connection with metal-working bits or tools; 10 and one object is to provide a simple and durable construction of ratchet-working mechanism capable of reversal to be operated in either direction by the workman, according to the nature of the locality or the surroundings at the place of use of the implement.

A further object is to provide improved means for feeding the drill-bit into the work as the cutting progresses, which feed mechanism is situated for convenient manipulation or adjustment.

A further object is to provide a novel sectional post adapted for use in connection with the ratchet mechanism and for holding the drill-bit up to the work, said post being 25 especially serviceable on work having its surfaces remotely situated, such as for service on the interior of steam-boilers. This feature of my invention provides for variation in the length of the center post to be adapted to 30 structures of different localities and conditions of use, and with the post is associated means for feeding or keeping the drill-bit in active relation to the work, such feed mechanism being readily operable without rotation 35 of the post.

With these ends in view the invention consists in the novel combination of elements and in the construction and arrangement of parts, which will be hereinafter fully described 40 and claimed.

To enable others to understand the invention, I have illustrated different embodiments thereof in the accompanying drawings, forming a part of this specification, and in which—

45 Figure 1 is a sectional elevation of a ratchet-drill mechanism used in connection with an elongated sectional central post embodying some of the features of my present invention.

Fig. 2 is a vertical sectional elevation of 50 another embodiment of the invention which employs a feed-screw equipped with a center

pivot and improved means for conveniently turning the feed-screw. Fig. 3 is a sectional plan view on the plane indicated by the dotted line 3 3 of Fig. 2. Fig. 4 is a fragmentary 55 sectional elevation illustrating the means for loosely sleeving the operating-lever on the notched tubular body of the ratchet-drill. Fig. 5 is a similar fragmentary detail sectional elevation of the means for loosely sleeving the 60 feed-screw-rotating devices.

The same numerals of reference are used to indicate like and corresponding parts in each of the several figures of the drawings.

The tubular body 10 of the drill is provided 65 at one end with a square or polygonal socket 11, adapted to receive the shank of the bit or any other suitable boring-tool, said body being also formed with a female threaded socket 12, adapted for the reception of a feed-screw, 70 as will hereinafter appear. Near the end in which the polygonal bit-socket is formed the tubular body is provided with an external annular collar 13, in which collar is produced a series of angular notches 14, which forms 75 the ratchet on the external face of the tubular body. In connection with this tubular body I employ a sectional two-part lever, which carries a feed-pawl adapted for engagement with the ratchet-collar and also carries an adjusting-spindle by which the feed-pawl may be retracted from engagement with the ratchet-collar and reversed relatively thereto for the purpose of making the pawl 80 coöperate with the ratchet on the operation 85 of the lever in one direction or the other.

Said lever consists of the members 15 16, which are joined firmly together by the thread-joint 17, consisting, preferably, of a female thread on the member 15 and a male thread on the 90 member 16, whereby the two parts of the handle may be readily separated or assembled. The inner member 15 of the lever is enlarged and fitted loosely on the tubular body, so as to have a loose sleeve connection therewith, 95 and near one side or face of the lever member 15 it is formed with a flange 18, adapted to ride or bear loosely against one face of the ratchet-collar 13. (See Fig. 2.) This lever member 15 is retained in place on the tubular body by means of a retaining-disk 19, which is screwed into an open side of the lever mem-

ber 15 opposite to the flange 18. Said retaining-disk is thus made fast at one side of the lever member 15 to impinge against the other face of the ratchet-collar 13 on the tubular body, and to prevent the disk from being disconnected accidentally on the lever member 15 I provide a locking device that holds the disk firmly connected to the lever member 15. This disk is provided with one or more notches 20 in one edge thereof, and in this notch is seated a key-pin 21, said pin having a longitudinal notch 22 in one edge thereof. The pin 21 is seated against the retracting-spring 23, contained in the socket 23^a of the lever member 15. (See Fig. 4.) The stop-screw 24 fits a suitable bearing in a part of the lever member 15 to enter the notch 22 of the key-pin 21, so that the pin is held against disengagement from the lever member 15, while the pin in turn holds the disk 19 against rotation and accidental disconnection from the lever member 15. It will thus be seen that the sleeve-formed end of the lever member 15 is fitted loosely on the tubular body to turn freely around the ratchet-collar thereon, and the flange 18 and the disk 19 coöperate with the ratchet-collar 13 to retain the lever member against movement lengthwise of the tubular body. The lever members 15 16 are hollow for the reception of an adjusting-spindle 25, adapted to carry the feed-pawl. Said spindle extends loosely through the hollow lever member 16, so as to project into the similar lever member 15, the outer end of the spindle being formed with a transverse locking - head 26. This head is adapted to be drawn by the tension of the pressure-spring, so as to fit within notches 27, produced in the end of the lever member 16, and the milled edges of this locking-head 26 on the adjusting-spindle normally lie flush with the cylindrical face of the lever member 16, whereby the lever may be manipulated in the hands of the operator without disturbing the position of the spindle or the action of the feed-pawl on the ratchet-collar of the tubular body. The engagement of the transverse head with the lever member 16 locks or confines the spindle against rotation and endwise movement within the hollow lever. At a point intermediate its length this adjusting-spindle is provided with a collar 28, the latter being formed on that part of the spindle which occupies the enlarged space within the lever member 15. This collar serves as a seat for one end of a coiled pressure-spring 29, fitted loosely on the adjusting-spindle 25 and adapted to be seated against the inner end of the lever member 16, whereby the spring 29 acts against the collar 28 to normally draw the spindle lengthwise of the lever and make the locking-head 26 fit in the notches 27 of the lever member 16, thereby maintaining the locking-spindle in practically a fixed position within the hollow lever. The feed-pawl 30 is connected operatively with the adjusting-spindle to be retracted on endwise movement of said spindle to a position where its nose will lie out of the path of the notches 14 of the ratchet-collar; but this feed-pawl is capable of free play or movement on the adjusting-spindle, so as to be operable with relation to the ratchet-collar independently of any adjustment of the spindle. The active end of the feed-pawl is formed with a beveled nose 31, adapted to fit into the notches of the ratchet-collar on the tubular body, and this pawl is furthermore provided with a longitudinal socket 32, adapted to loosely receive the inner end of the adjusting-spindle 25. The pawl carries a transverse pin 33, which passes through a short slot 34, which is produced longitudinally in the spindle 25, near the inner end thereof, and against the heel of this 80 85 90 95 100 named views, Figs. 2 and 3. The short feed-screw 36 has threaded engagement with the socket 12 in the tubular body 10, and the exposed protruding end of this feed-screw is formed with a central pivot 37, said pivot 37 being an integral part of the short feed-screw. Said feed-screw is furthermore provided with an annular collar 38 between its threaded shank and the center pivot, and in this collar is formed a series of radial pockets 39, adapted to receive a feed-pin 48, which may be thrust successively into said pockets for rotating the screw. This feed-screw is supported idly by a feed-sleeve 40, which loosely embraces a smooth part of the screw and a collar 38 thereon, said feed-sleeve being formed or provided with a tubular extension 41. A retaining-disk 42 is screwed into a threaded opening in the feed-sleeve 40, and this retaining-disk 42 cooperates with a rib 40^a on the feed-sleeve in holding the latter against endwise displacement relatively to the collar 38 on the feed-screw, whereby the sleeve 40 is normally confined in a loose condition and in operative relation to the collar 38 on the screw 36. The retaining-screw 42 is held in place by means of the locking contrivance shown by Fig. 5, said disk having a notch 43 to receive a key-pin 44, which is formed with a notch 45. A stop-screw 46 is fitted in the sleeve 40 to engage with a notch 44 of the key-pin, and against this pin operates a spring 47, which is seated in a socket formed within the sleeve 40, all as clearly shown by Fig. 5.

The operating-pin 48 for rotating the feed-screw is fitted loosely in the tubular extension 41 of the sleeve 40, and the pointed innerend 49 of this pin is adapted to fit in either of the apertures 39 of the collar on the feed-screw, thus temporarily making the operating-pin fast with the feed-screw, so as to rotate the latter in the socket 12 of the tubular body, and thereby advance the drill-bit into the work. The screw-operating pin is confined against displacement in the tubular extension 41 by means of a stop-screw 51, which is attached to the extension 41 and plays in a groove 50, which is cut in one face of the operating-pin 49, said slot being long enough to allow the pin to be withdrawn from one aperture before its endwise movement is arrested by the stop-screw 51.

The tubular body, the lever, and the ratchet-bit mechanism of my invention may be used in connection with the elongated sectional post and an extended feed-screw of the character represented by Fig. 1 of the drawings, and in this adaptation of my invention the sleeve 40, the operating-pin 49, and the feed-screw 36 are omitted. The device shown by Figs. 2 and 3 is especially intended for use on work having parts thereof arranged at such a distance apart as to accommodate the feed-screw and other parts of the implement; but in some classes of work the surfaces are disposed quite remote. Hence it has heretofore been necessary to employ blocks and other

contrivances to furnish a bearing for the pivot-screw. I overcome this objection by the provision of a center post of elongated sectional construction and by the employment of a long feed-screw which has loose engagement with the center post and is equipped with a feed-nut that finds a bearing against a part of the center post.

The center post 52 relating to this part of my invention is of sectional separable construction, as shown by Fig. 1, and it consists, essentially, of a tubular member 53, one or more solid members 54, and a coupling 55. In the drawings I have shown the post as having a single solid member 54; but it is evident that the number of these parts may be duplicated, according to the desired length of the post and the nature of the work. The contiguous ends of the members 53 54 are provided with male screw-threads adapted to engage with female threads on the coupling 55, which serves to separably unite the members and to dispose them in alinement one with the other. The outer end of the sectional post is equipped with a central pivot 56, having a threaded end which is screwed into a coupling 57, that is united to the outer extremity of one member 54 of the post; but it is evident that the member 54 and coupling 57 may be omitted, so that the pivot-screw 56 may be screwed into the coupling 55, thus shortening the post.

The feed-screw 58 is provided at a point between the ordinary running thread 61 and the machine-thread 62 with a smooth annular collar 59, said collar having a plurality of radial holes 60, adapted to receive a pin by which the screw may be rotated, if desired; but ordinarily I do not find it desirable to resort to this expedient of a pin for rotating the screw, because a feed-nut 63 is provided for engagement with the machine-thread 62. That part of the feed-screw having a running thread 61 is screwed into the threaded socket 12 of the tubular body, while the remaining length of the feed-screw, having the machine-thread 62, is fitted loosely in the tubular member 53 of the sectional center post. The feed-nut 63 is screwed on the threaded part 62 of the feed-screw to have bearing against the end of the tubular member 53 on the post, said post having a bearing against a part of the work by means of the center pivot 56. By rotating the feed-nut 63 the screw 58 may be advanced in order to move the tubular body and the drill toward the bottom of the cut in the work, and thus the bit may be kept in active relation to the work by proper manipulation of the feed-nut, which controls the feed-screw, without, however, rotating the tubular post, because the screw 58 has its length 62 confined loosely in the post, so that the feed-nut will bear against one end of said post. The post and feed-screw (shown by Fig. 1) may be used in any desired position, either horizontally, vertically, or inclined, on many different kinds of work; but a special

merit of this part of the invention resides in the adaptability of the post and screw to interior work on steam-boilers, in which it is difficult to use ordinary drilling appliances 5 because of the narrow space therein.

Changes may be made in the form and proportion of some of the parts while their essential features are retained and the spirit of the invention embodied. Hence I do not de-
10 sire to be limited to the precise form of all the parts as shown, reserving the right to vary therefrom.

Having thus described the invention, what I claim is—

15 1. In a ratchet-drill of the class described, the combination with a socketed body having a ratchet, of a lever, a spindle carried by said lever, and a pawl connected loosely with said spindle to operate independently of any move-
20 ment thereof and capable of reversal with said spindle, substantially as described.

25 2. In a ratchet-drill of the class described, the combination with a socketed body having a ratchet, of a lever having a sleeved connec-
30 tion with said body, a spring-actuated spindle within said lever, and a spring-actuated pawl connected loosely with the spindle to operate independently thereof and capable of reversal therewith within said lever, sub-
35 stantially as described.

35 3. In a ratchet-drill of the class described, the combination with a ratchet-formed body, of a hollow lever connected loosely with said body, a spring-actuated and slotted spindle having interlocking connection with the body and reversible therein, a pawl mounted loosely on said spindle and carrying a pin adapted to play in the slot of the lever, and a spring seated against the pawl and the spindle, whereby the pawl may operate independently of any play of the spindle and is connected thereto for reversal therewith within the lever, substantially as described.

40 4. In a ratchet-drill of the class described, the combination with a ratchet-formed body, of a hollow lever having a sleeve connection therewith, a disk united to said lever by a threaded joint, a spring-seated key-pin connected to the lever and engaging a notch in
45 the disk, a stop-screw engaging the pin, a spindle loosely mounted in the lever, and a pawl mounted loosely upon the spindle and movable independently thereof into and out of engagement with the ratchet-formed body, substantially as described.

55 5. In a ratchet-drill of the class described, the combination with a ratchet-formed body, of a lever loosely mounted thereon, a spindle carried by the lever and reversible there-
60 in, a feed-pawl connected slidably to the lever to play or move thereon independently

of any adjustment of the spindle, a pressure-spring acting against said spindle to hold the same in interlocking engagement with the lever, another spring acting on the pawl to hold the latter normally in engagement with the ratchet on the body, a feed-screw connected operatively to said body, and means for rotating said screw, substantially as described.

7c 6. In a ratchet-drill of the class described, the combination of a body, a lever and ratchet devices for rotating the body by movement of the lever, of a sectional post having a removable center pivot adapted for interchangeble connection with the several sections of the post, and a feed-screw between said post and the body, substantially as described.

75 7. In a ratchet-drill of the class described, the combination with a body, a lever and ratchet devices, of a sectional post including a hollow member, a feed-screw having threaded engagement with the body and fitted loosely to the hollow member of said post, a feed-nut seated against the post and having threaded engagement with the feed-screw, and a removable center adapted for interchangeable connection with the sections of the post, substantially as described.

90 8. In a ratchet-drill of the class described, a sectional center post comprising a plurality of members, a removable center pivot adapted for interchangeable connection with the several sections of the post, and couplings which unite the members separably together and connect the center pivot to one member, in combination with a socketed body, means for rotating said body, and a feed-screw connected operatively with the body and said post, substantially as described.

95 9. In a ratchet-drill of the class described, a sectional post comprising a tubular member, a solid member, a removable center pivot adapted for interchangeable connection with the several sections of the post and threaded couplings between said parts, combined with a socketed body, means for rotating said body, a feed-screw having threaded engagement with the body and a loose engagement with the hollow member of the post, and a feed-nut threaded on the screw and seated against the hollow post member, substantially as described.

110 In testimony that I claim the foregoing as my own I have hereto affixed my signature in the presence of two witnesses.

ANDREW KLAY.
